CLAIM

We claim the ornamental design for a chair, as shown and described.

DESCRIPTION

FIG. 1 is a top front left perspective view of our new design;

FIG. 2 is a front view thereof;

FIG. 3 is a rear view thereof;

FIG. 4 is a left side view thereof;

FIG. 5 is a right side view thereof; and,

FIG. 6 is a top view thereof.

The views of the chair not shown form no part of the claimed design. The broken lines in the figures show portions and features of the chair that form no part of the claimed design.

1 Claim, 6 Drawing Sheets(56)
